D. P. LACEY, OF ORFORDVILLE, WISCONSIN

Letters Patent No. 64,112, dated April 23, 1867.

IMPROVEMENT IN SHOWER BATHS.

The Schedule referred to in these Letters Patent and making part of the same.

TO ALL WHOM IT MAY CONCERN:

Be it known that I, D. P. LACEY, of Orfordville, in the State of Wisconsin, have invented certain new and useful improvements in Portable Bath-Tubs; and I do hereby declare that the following is a clear, full, and exact description of the same, reference being had to the accompanying drawings, and to the letters of reference marked thereon, in which—

Figure 1 represents a side elevation, with a part of the tub removed, in order to exhibit the manner of working the valve.

Figure 2 is a perspective of the frame, showing its mode of construction.

Figure 3 represents the valve-cap; and

Figure 4 the bottom of the tub, showing the perforations therein.

The object of this invention is to produce a bath-tub of such simplicity and economy that its advantages may be enjoyed by almost all who choose to adopt this mode of bathing; and in order, therefore, that others may avail themselves of its benefits, I will now describe its construction and operation.

A represents the bottom, which is provided with a circular hole in its centre for the purpose of holding a vessel to catch the water as it falls; the bottom may be slightly inclined, to allow of the waste water running off. b b represent the uprights, which are provided with holes in their bottom ends, which slip over pins in bottom A. B represents the cross-piece, with holes in each arm to fit on the top ends of the uprights. e e are braces, which are hinged on to the uprights. a a are the legs, and are adjusted in the same manner as are the uprights b b. C represents an ordinary tub, which has a hole in its bottom; over this hole is secured a metal plate or valve, which is perforated with small holes, as seen in fig. 4. a is a standard, to which is pivoted the lever g. h represents the valve-cap; said cap is provided with a semicircular piece of metal, n, with a notch at one end to prevent the lever from slipping off; this feature is clearly seen in fig. 1. k is a hook by which the tub is suspended. m is a cord, which is secured to the lever; both ends of the cord should hang down, as one opens the valve, while the other closes it.

The operation of my invention is as follows: The tub C is filled with water; the lever is now pulled by one end of the cord, which takes the direction of the notch on the circular piece of metal, thereby forcing up the valve-cap, making an exit for the water. When it is desired to stop the fall of water, it is only necessary to pull on the other end of the cord, which at once forces the lever back on the circular piece of metal, thus effectually and instantly shutting the water off. Should it be necessary, a piece of oil-cloth may be suspended, by means of hooks or otherwise, around the frame, in order to give greater privacy while performing your ablution; which, after being performed, the entire arrangement may be easily and quickly taken down and put out of sight.

Having thus fully described my invention, what I claim, and desire to secure by Letters Patent, is—

1. Constructing and operating the valve, substantially as and for the purpose set forth.
2. The valve arrangement, constructed as specified, in combination with a vessel for containing water, substantially as set forth.

In testimony whereof I set my hand in presence of two witnesses.

D. P. LACEY.
